UNITED STATES PATENT OFFICE.

ISIDOR DREYFUS, OF NEW YORK, N. Y.

DESIGN FOR A ROPE FOR PORTIÈRES, &c.

SPECIFICATION forming part of Design No. 26,664, dated February 16, 1897.

Application filed June 30, 1896. Serial No. 597,646. Term of patent 7 years.

To all whom it may concern:

Be it known that I, ISIDOR DREYFUS, a citizen of the United States, and a resident of the city of New York, in the county of New York and State of New York, have invented a new and original Design for a Rope for Rope Portières and Lambrequins, of which the following is a specification.

In the accompanying drawing, forming a part of this specification, one strand of my new design of ropes for rope portières and lambrequins is shown.

The leading feature of my design consists of a rope having tufts, having approximately the shape of a pine cone and composed of a series of superimposed loops and a cord ruff at the bottom.

In the drawing, A is the rope; B, the tuft; b, the loops; C, the ruff.

What I claim is—

The design for a rope for rope portières and lambrequins, substantially as herein shown and described.

In testimony that I claim the foregoing as my invention I have signed my name, in presence of two witnesses, this 4th day of June, 1896.

ISIDOR DREYFUS.

Witnesses:

OSCAR F. GUNZ,
D. PETRI-PALMEDO.
